UNITED STATES PATENT OFFICE.

ADELMER M. BATES, OF CHICAGO, ILLINOIS, ASSIGNOR TO BATES VALVE BAG COMPANY, OF CHICAGO, ILLINOIS, A CORPORATION OF WEST VIRGINIA.

RING-FORMING MACHINE.

1,071,386.

Specification of Letters Patent. Patented Aug. 26, 1913.

Application filed June 12, 1912. Serial No. 703,191.

To all whom it may concern:

Be it known that I, ADELMER M. BATES, a citizen of the United States, residing at Chicago, in the county of Cook and State of Illinois, have invented a certain new and useful Improvement in Ring-Forming Machines, of which the following is a specification.

My invention relates to machines for forming and electrically welding wire rings.

It is illustrated in the accompanying drawings, wherein—

Figure 1 is a side elevation; Fig. 2 is a plan view with parts shown in section on the line 2—2 of Fig. 1; Fig. 3 is a vertical cross-section on the line 3—3 of Fig. 2; Fig. 4 is a vertical cross detail section on the line 4—4 of Fig. 2; Fig. 5 is an inner elevation of a movable former disk; Fig. 6 is an inner elevation of a fixed former disk; Fig. 7 is a cross-section through the former disks; Fig. 8 is a completed ring.

Like parts are indicated by the same letters in all the figures.

A is a base on which the several parts are suitably mounted. A¹, A² and A³ are standards secured to and rising from such base.

The ring former.—B is the fixed former disk secured to the standard A¹ and provided with an annular groove on its inner face to receive the movable former ring B¹ which contains the semi-circular groove B² and is cut away at B³. The movable former disk B⁴ is cut away at B⁵ and provided with an annular groove to receive the former ring B⁶ which contains the semi-circular groove B⁷. The disk B⁴ is attached to the end of a bar B⁸ which slides in a bearing in the upper part of the standard A². This bar is provided with a pocket B⁹ containing a spring B¹⁰ which bears against the end B¹¹ of a bar B¹² which slides through a bearing in the upper part of the standard A³ and has a collar B¹³ adapted to be fixed in position by the set screw B¹⁴. About the bars B⁸ and B¹² is the spiral spring B¹⁵ which bears against the standard A² and the collar B¹³ and normally operates to draw the movable former disk away from the fixed former disk.

B¹⁶ is a head secured to the bar B¹² and carrying at one side the idler B¹⁷ in the path of the cam B¹⁸. This cam tends to hold the parts in the position shown in Fig. 3, that is, with the two former disks in engage-

ment except during the short interval when the idler B¹⁷ is opposite the mutilated portion of the cam. At such times the spring B¹⁵ retracts the movable former disk B⁴. The spring B¹⁰ operates to yieldingly connect the bars B⁸ and B¹².

The wire feeder.—C is one of the wire guides suitably supported on the frame and provided with a hole through which the wire C¹ moves. This guide contains the block C² adjustably secured in position by the set screw C³ at one side of the hole through which the wire C¹ is to be fed forward. C⁴ is a roller traveling in the pocket C⁵ with the inclined wall C⁶ and opposed to the block C². C⁷ is a rod having a head C⁸ which abuts against the roller C⁴ and the spiral spring C⁹ which lies between the wall or pocket C² and the back of the head C⁸ and tends to keep the roller C⁴ against the block C² so as to lock the wire in position. C¹⁰ is another wire guide with a hole through which the wire passes. It is suitably supported on the frame.

D and D¹ are shafts mounted in suitable standards which rise from the base A. On the shaft D is secured the disk D² and on the shaft D¹ is secured the disk D³. Each of these shafts is provided with a series of arc openings D⁴ D⁴ through which project the bolts D⁵ D⁵ whereby it is possible to adjustably secure in position the mutilated feeding disks D⁶ D⁷. The rotation of these shafts will cause the feeding disks to rotate in the direction indicated by the arrows in Fig. 1 and they are arranged and timed so that when they have completed their rotational excursion for any given operation of machine, they will have forced the wire through the opening D⁸, the groove B⁷ and the groove B² until the ring is formed and its two ends overlap as indicated in Fig. 2. The further rotation of the feeding disks presents their mutilated portion to the wire so that the feeding is interrupted while the wire is held in position by means of the clamping roller C⁴ and block C².

The welding mechanism.—The ring is now in position to be welded. E is the fixed electrode held in the block E¹ by the set screw E². The block is insulated as indicated at E³ and to it is secured one end of the conductor E⁴ by means of the bolts E⁵, the other end being secured by the bolt E⁶ to a terminal E⁷ of the transformer. The

- parts are so positioned that the end of the electrode E is in close proximity to the overlapped end of the wire of which the ring is to be formed as indicated in Fig. 2.
- 5 F is the movable electrode held by the set screw F¹ in the copper block F² which is surrounded by an insulation bearing F³ in the upper end of the standard A² and is provided with a pocket having an insulated lining F⁴ to receive the end of the bar F⁵. This bar F⁵ has at its outer end the yoke F⁶ and it is squared and passed through the bearing F⁷. Between the outer arm of the yoke and the bearing F⁷ is the spiral spring F⁸, which tends to keep the electrode F in its retracted position as indicated in Fig. 3.
- F⁹ is an arm secured to the yoke and the bar by the screw bolt F¹⁰ and screw-threaded into the arm F⁹ is the pocket F¹¹ closed 10 at its outer end by the nut F¹² and provided with the spiral spring F¹³ which bears against the piston head F¹⁴ on a rod F¹⁵, the end of which is in the path of a roller F¹⁶ on a rocking arm F¹⁷ pivotally secured on 15 a suitable standard at the point F¹⁸ and provided at its other end with the roller F¹⁹ in the path of the cam F²⁰ screwed on the shaft D¹. Thus the rotation of this shaft at a properly predetermined period 20 rocks the arm F¹⁷ and thus moves the movable electrode forward against the overlapped wire portions of the ring. The movement of these electrodes takes place in a free space formed by the cutting away of 25 the two former disks and they move laterally toward each other. The spring F¹³ is relatively strong and serves in the first instance as a means for transmitting motion from the shaft through the roller F¹⁶ 30 to the movable electrode F, but it also serves to press the two electrodes together as the metal between them is softened in response to the passage of the electric current.
- F²¹ is the flexible conductor attached at 35 40 45 50 55 60 65 70 75 80 85 90 95 100 105 110 115 120 125 130
- 40 F²¹ is the flexible conductor attached at F²² to the block F² and at the other end by the set screw F²³ to the terminal F²⁴ of the converter.
- To apply the current to perform the act of welding I provide the following mechanism: On the shaft D is the beveled gear G meshing with the beveled gear G¹ on the transverse shaft G² mounted in suitable bearings G³ G⁴ and provided at its outer end with the cam G⁵ which is in the path of a roller G⁶ in the yoke G⁷ on the rod G⁸ which moves through bearings G⁹ G¹⁰ and is provided with the circuit-closing head G¹⁰ and the spiral spring G¹¹.
- G¹² is a circuit-closing head on the rod G¹³ which is mounted in the bearing G¹⁴ and provided with the spiral spring G¹⁵. By bringing these two circuit-closing heads G¹⁰ and G¹² together the circuit is closed through the transformer and the generator G¹⁶ by means of the conductors G¹⁷ and G¹⁸.

The parts are so arranged and timed that when the electrodes have been forced together with the overlapping parts of the ring wire between them, the switch is then closed and the induced current sent through the electrodes and overlapping wire so as to complete the weld.

The ring severing mechanism.—Rising from the upper part of the standard A² is the arm J which carries a bearing J¹ through which the knife bar J² vertically reciprocates. This bar is shouldered at J³ and a spiral spring J⁴ is inclosed within the bearing J¹ and normally serves to keep the knife in its elevated position. At the lower 75 80 85 90 95 100 105 110 115 120 125 130

end of the knife bar is the knife edge J⁵. Opposed to it is the knife J⁶ secured by the set screw J⁷ to the former disk B⁴ at one side of its cut-away portion. This knife when the parts are in the position shown in Fig. 2 lies directly under the feed portion of the wire. The knife bar J² projects upwardly and abuts against one end of the rock lever J⁸ pivotally mounted at J⁹ and provided with a roller J¹⁰ at its other end. This roller is in the path of the cam J¹¹ on the disk D³ and the parts are so timed that this cam encounters the roller J¹⁰ and depresses the knife edge so as to sever the wire as soon as the ring has been formed by the welding of these two parts together. The parts are now in the position indicated in most of the figures. The ring, however, has now been completely formed and must be discharged from the machine.

The ring discharging means.—As previously suggested, the ring forming disks are to be separated for this purpose and this is accomplished by the spiral spring B¹⁵, for the parts are so set and adjusted that when the mutilated portion of the cam B¹⁸ is opposed to the idler B¹⁷ the spiral spring B¹⁵ is free to operate and retract the bar and with it the movable former disk B⁴, because the shafts B¹² and B⁸ are linked together by means of the pin W working in the slot W¹. The two shafts D and D¹ are operatively connected by means of the end mesh gear wheels K K¹ and the whole device can be driven by imparting motion to either of these shafts from any desired source. The transformer is preferably mounted as indicated in Fig. 1 on the base.

It will be understood that many of the details and parts illustrated and described could be greatly altered and changed in structure, form, relation and proportion with reference one to another without departing from the spirit of my invention.

While I have illustrated an operative structure, the drawings are to be taken simply as a diagrammatic illustration rather than as working drawings. Some of the supporting and connecting parts and portions of the frame and driving mechanism

have not been very elaborately set forth, all such matters being easily within the knowledge of an ordinary mechanic.

5 The order in which the several operations are performed might be to some extent varied if desired and the overlapping portions of the wire which forms the ring might be overlapped in the plane of the ring rather than laterally.

10 The use and operation of my invention are as follows: The wire is forcibly fed forwardly to form the ring. It is not stamped or forced bodily into a forming cavity, nor is it drawn or wound into or upon a former.

15 It is forced forwardly through wire guiding and straightening devices and then into a ring forming cavity, being advanced by an action which, touching the coil of wire is a drawing action and touching that portion 20 of the wire which forms the ring, is a pushing action. This operation continues until the ring has been formed or its two parts overlapped, whereupon the feeding movement ceases temporarily and the two electrodes are brought together in a free or open

25 space with the overlapped wires between them. When this has been accomplished, the further movement of the operating parts of the machine applies the electric current, 30 which passing through the electrodes and the wire forms the weld. Then if that be

the desired order of the several steps, a further movement of the mechanism brings the knife down upon one strand of the wire so 35 as to sever the ring from the coil of wire. This, however, is preferably done as indicated so as to leave the end of the wire straightened, and passing through the two guides where it is held by the clamp, from

40 being retracted by the resiliency of the wire in the coil. The parts are then timed so that by the further operation of the machine the former disks are separated and the completed ring is permitted to drop out 45 from between them. The disks are then brought together and the parts are in readiness to repeat the operation or series of steps, the wire being fed in as before.

I claim:

50 1. In a ring forming machine the combination of a former having a ring-shaped hole of substantially fixed cross sectional area therein with means for feeding the wire through such hole until its two parts overlap, means for uniting the wire at the overlap, means for subsequently cutting the ring from the wire and means for releasing the finished ring from the former.

55 2. In a ring forming machine the combination of a former having a ring-shaped hole therein and an opening at its periphery into which the hole opens with means for feeding wire through such hole until its two parts overlap in the opening, means for uniting the wire at the overlap, means for

subsequently cutting the ring from the wire and means for releasing the finished ring from the former.

3. In a ring forming machine the combination of a former consisting of two disks 70 having grooves to form a ring-shaped hole with means for feeding the wire through such hole until its two parts overlap, means for uniting the wire at the overlap, means for cutting the ring from the wire and means for releasing the finished ring from the former.

4. In a ring forming machine the combination of a former having two disks containing each a portion of a groove adapted 80 when brought together to form a ring-shaped hole in the former with means for feeding the wire through such hole until its two parts overlap, means for uniting the wire at the overlap, means for cutting the ring from the wire and means for releasing the finished ring from the former.

5. In a ring forming machine the combination of a former having a ring shaped hole therein, its two parts lying in different planes, with means for feeding the wire through such hole until its two parts overlap, means for uniting the wire at the overlap, means for cutting the ring from the wire and means for releasing the finished 95 ring from the former.

6. In a ring forming machine the combination of a former having a ring-shaped hole whose two parts lie in different planes and a peripheral opening into which the 100 hole opens with means for feeding the wire through such hole until its two parts overlap in the opening, means for uniting the wire at the overlap, means for cutting the ring from the wire and means for releasing the 105 finished ring from the former.

7. In a ring forming machine the combination of a former having two disks movable with reference to each other and containing each a portion of a ring-shaped hole 110 with means for feeding the wire through such hole until its two parts overlap, said means comprising opposed rotating disks between which the wire travels, means for uniting the wire at the overlap, means for 115 cutting the ring from the wire and means for releasing the finished ring from the former.

8. In a ring forming machine the combination of a former having a ring-shaped hole 120 of substantially fixed cross sectional area therein with a tangentially arranged hole leading therefrom with means for feeding the wire through such tangentially arranged hole and through such ring-shaped hole until its two parts overlap, means for uniting the wire at the overlap, means for cutting the ring from the wire and means for releasing the finished ring from the former.

9. In a ring forming machine the combi- 130

lap, means for subsequently cutting the ring from the wire comprising a reciprocating knife on one side of the wire and a knife edge on the other side, said knife edge attached to the former, and means for releasing the finished ring from the former.

21. In a ring forming machine the combination of a former having a ring-shaped hole of substantially fixed cross sectional area therein and a peripheral opening into which the hole opens with means for feeding the wire through such hole until its two parts overlap in such opening, means for uniting the wire at the overlap in the opening, means for subsequently cutting the ring from the wire in the opening and means for releasing the finished ring from the former.

22. In a ring forming machine the combination of a former having a ring-shaped hole of substantially fixed cross sectional area therein and a peripheral opening into which the hole opens with means for feeding the wire through such hole until its two parts overlap in such opening, means for uniting the wire at the overlap in the opening, means for subsequently cutting the ring from the wire in the opening comprising a knife mounted on the former and a knife adapted to reciprocate in the former.

23. In a ring forming machine the combination of a former having two disks containing a ring-shaped hole with means for feeding the wire through such hole until its two parts overlap, means for uniting the wire at the overlap, means for cutting the ring from the wire and means for separating the disks to release the finished ring from the former.

24. In a ring forming machine the combination of a former having a ring-shaped hole of substantially fixed cross sectional area therein with means for feeding the wire through such hole until its two parts overlap, means for uniting the wire at the overlap while it is at rest, means for subsequently cutting the ring from the wire while the wire is at rest, and means for releasing the finished ring from the former.

25. In a ring forming machine the combination of a former having two disks, one of them movable containing a ring-shaped hole, with means for intermittently feeding the wire through such hole until its two parts overlap, means for uniting the wire at the overlap, means for cutting the ring from the wire and means for releasing the finished ring from the former.

26. In a ring forming machine the combination of a former having a ring-shaped hole of substantially fixed cross sectional area, a wire feeder to feed the wire through such hole, an electric welder including a pair of electrodes to unite the wire to form the ring, a cutter and means for operating it subsequently to sever the ring from the

wire, means for releasing the finished ring from the former and a shaft with which the wire feeder rotates, a cam mounted thereon and means driven thereby to move one of the electrodes toward the other.

70

27. In a ring forming machine the combination of a former having a ring-shaped hole of substantially fixed cross sectional area, a wire feeder to feed the wire through such hole, an electric welder including a pair of electrodes to unite the wire to form the ring, a cutter and means for operating it subsequently to sever the ring from the wire, means for releasing the finished ring from the former, a driving shaft, means driven thereby to bring the electrodes together and means driven by said shaft to close the circuit through the electrodes.

75

28. In a ring forming machine the combination of a former having a ring-shaped hole of substantially fixed cross sectional area, a wire feeder to feed the wire through such hole, an electric welder including a pair of electrodes to unite the wire to form the ring, a cutter and means for operating it subsequently to sever the ring from the wire, means for releasing the finished ring from the former, a driving shaft, means driven by said shaft to close the circuit through the electrodes, said electrode moving and circuit closing means arranged to operate in succession.

80

29. In a ring forming machine the combination of a former having a ring-shaped hole of substantially fixed cross sectional area, a wire feeder to feed the wire through such hole, an electric welder to unite the wire to form the ring, a cutter and means for operating it subsequently to sever the ring from the wire, means operating in unison with the wire feeder to operate the wire cutter, said means timed to cut the wire after the ring is formed and means for releasing the finished ring from the former.

90

30. In a ring forming machine the combination of a former having a ring-shaped hole of substantially fixed cross sectional area therein with means for feeding the wire through such hole until its two parts overlap, said hole being of substantially the same cross-sectional area as the wire, means for uniting the wire at the overlap, means for subsequently cutting the ring from the wire and means for releasing the finished ring from the former.

100

31. In a ring forming machine the combination of a former having a ring-shaped hole of substantially fixed cross sectional area therein and an opening at its periphery into which the hole opens with means for feeding wire through such hole until its two parts overlap in the opening, said hole being in substantially the same cross-sectional area as the wire, means for uniting the wire at the overlap, means for subsequently cutting the ring from the wire and means for releasing the finished ring from the former.

110

115

120

125

130

quently cutting the ring from the wire and means for releasing the finished ring from the former.

32. In a ring forming machine the combination of a former having a ring-shaped hole therein with means for feeding the wire through such hole until its two parts overlap, means for uniting the wire at the overlap, means for cutting the ring from the wire and means for releasing the finished ring from the former, the ring-shaped hole being completely inclosed within the body of the former except at the point where the wire ends overlap.
33. In a ring forming machine the combination of a former having a ring-shaped hole therein and an opening at its periphery into which the hole opens with means for feeding wire through such hole until its two parts overlap in the opening, means for uniting the wire at the overlap, means for cutting the ring from the wire and means for releasing the finished ring from the former, the ring-shaped hole being completely inclosed within the body of the former except at the point where the wire ends overlap.
34. In a ring forming machine a former made up of a pair of opposed parallel disks

each of said disks having a circular groove 30 of semi-circular cross-sectional area on one side said grooves in the two disks being in opposition one to the other, means for pressing said disks together, means for forcing the wire through the hole formed by said 35 grooves until the free end overlaps the body of the wire, means for attaching the overlapping ends and means for severing the wire.

35. In a ring forming machine a former 40 made up of a pair of opposed parallel disks each of said disks having a circular groove of semi-circular cross-sectional area on one side said grooves in the two disks being in opposition one to the other, means for pressing 45 said disks together, means for forcing the wire through the hole formed by said grooves until the free end overlaps the body of the wire, means for attaching the overlapping ends and means for severing the 50 wire and means for subsequently spreading the disks and freeing the ring.

Signed at Chicago, Illinois, this 8th day of June 1912.

ADELMER M. BATES.
